UNITED STATES PATENT OFFICE.

RAYMOND M. BROWN, OF NEWPORT NEWS, VIRGINIA.

BOTTLE OPENER.

Application filed October 22, 1926. Serial No. 143,463.

Hotel operators have experienced considerable damage to furniture caused by patrons attempting to remove metal caps from bottles by squeezing said caps between the edges of drawers or between doors and door frames, also by placing such caps on the edges of furniture; also by placing corks in similar positions; another source of damage arises from patrons screwing hooks of various kinds in woodwork upon which to hang a razor strop, and it is the purpose of my invention to provide a neat, compact and efficient composite article which can be sold to hotels, and other concerns, which will entirely eliminate this source of damage and at a comparatively small price.

My invention comprises a new article of manufacture having common base, a cork screw, a bottle cap puller, and a razor strop hook.

In the drawings:

Figure 1 is front elevation of my improved article of manufacture.

Figure 2 is a vertical longitudinal section of Figure 1.

The reference numeral 1 designates the base which is provided with a substantially V shaped intermediate portion formed by the legs 2 and 3. At the apex of this V shaped portion there is found a lip 4 constituting a contact portion adapted to catch under the edge of a bottle cap, as shown in said patent, there being an ear 5 on the base, which constitutes another contact portion, such portion functioning as a fulcrum against which the bottle cap rests when the cap is being removed from the bottle.

At the bottom edge of the base 1 I form a hook 6 upon which a razor strop may be hung.

At the apex of the legs 2 and 3 and on the outside thereof I provide two spaced ears 7,

between which I pivotally secure one end of a cork screw 8 which, when not in use, will lie above and along the leg 2, and when in use will be moved to the position shown in dotted lines. Now it is desirable to lock the cork screw in its inoperative position, and for this purpose I provide the base 1 with an undercut lug 9 which is slightly off center relatively to the longitudinal axis of the cork screw, so that in order to lock the cork screw to the lug 9 it is necessary to flex the cork screw slightly to one side so that the point of the screw may pass under the lug. Care should be taken to have the lug 9 in proper position to eliminate all possibility of the cork screw being flexed beyond the limits of its flex, thereby maintaining the necessary flexibility of the screw during the life of the article.

From the above it will be seen that I have provided a cheap, simple, ornate composite article of manufacture which may be securely fastened in a bath or other room by means of which caps and corks may be quickly removed from bottles and by which razor strops may be suspended, and by the use of this article damage to furniture and wood work is entirely avoided, which will result in a very material saving to hotels, etc.

What I claim is:

A cork remover having a base designed to be secured to a flat surface and provided with a hollow forwardly projecting recessed portion intermediate the ends thereof, a corkscrew pivotally mounted exteriorly of said portion to swing in a vertical plane, and means on the upper end of said base for holding the end of said corkscrew in inoperative position.

In testimony whereof I affix my signature.

RAYMOND M. BROWN.
